[57] CLAIM

The ornamental design for a knife or similar article, as shown and described.

DESCRIPTION

FIG. 1 is a side elevational view of a knife or similar article showing my new design;

FIG. 2 is a right edge elevational view thereof;

FIG. 3 is an end elevational view from the top of FIG. 1;

FIG. 4 is an enlarged cross-sectional view taken on line 4—4 of FIG. 1; and

FIG. 5 is an enlarged cross-sectional view taken on line 5—5 of FIG. 1.

The side and edge opposite the handle portion shown in FIGS. 1 and 2 are similar to the respective side and edge shown.

The distinguishing feature of my new design for a knife or similar article resides in the handle configuration.
